Design No. 502.
James Fullay
Assign to Johnson, Cox & Fullay
Barber Chair Design

Patented September 14, 1852

Des. 502

James J. Dulley of Troy, N.Y.
Assignor to
Johnson Cox & Fuller of same place
Letters Patent No. 502 Dated Sept. 14, 1852

The schedule referred to in these Letters Patent and making part of the same

To all whom it may concern:

Be it known that I, James J. Dulley of Troy, in the County of Rensselaer, and State of New York, have invented or produced, a new and original design of bottom, front & top plates, for Parlor Stoves, which Stoves I call the "Home Parlor No. 5" and I do hereby declare, that the following is a full, clear and exact description of the same, reference being had to the annexed drawings, making a part of this specification, in which Fig. 1 is a direct or top view

of the bottom plate. Fig. 2. is a view of the front and Fig. 3 a view of the top plates.

The ornamental design of my stone plates consists of the gothic mouldings (a) & (b) and the ornament (c) arranged so as to form the bordering of the bottom plate. The design of the front plate consists in the arrangement of gothic mouldings, so as to form the arches (d, e f & g) - two of the arches i.e. (d) and (f) are supported on the gothic columns (h, h) and (i, i) the top moulding (j) is ornamented with the drops (k, k) the outer panel is ornamented with the diamond work (l) & ornament (m). - the design of the top plate, consists of the ornamental gothic moulding (n) arranged around and forming the border of the top.

Having thus described my design of parlorstone plates.

What I claim as new and desire to secure by Letters Patent, is the ornamental design & configuration of stove plates, the same as herein described and represented in the annexed drawings.
